UNITED STATES PATENT OFFICE

97,452

DESIGN FOR A COMBINATION HAND BAG AND CAMERA OR SIMILAR ARTICLE

Theodore Ball, New York, N. Y.

Application September 3, 1935, Serial No. 58,410

Term of patent 3½ years

To all whom it may concern:

Be it known that I, Theodore Ball, a citizen of the United States, residing in the city of New York, county of New York, and State of New York, have invented a new, original, and ornamental Design for a Combination Hand Bag and Camera or Similar Article, of which the following is a specification, reference being had to the accompanying drawings, forming part thereof.

Figure 1 is a front view of a combination handbag and camera or similar article, showing my new design, the closure flap being fastened;

Figure 2 is an end view, the closure flap being fastened;

Figure 3 is a view similar to Figure 1, the closure flap being unfastened and folded back;

Figure 4 is a top plan view, the closure flap being unfastened and folded back.

When the closure flap is closed the rear of the camera is entirely concealed thereby, but in other respects both sides of the bag have substantially the same appearance.

The dominant feature of the present design resides in the ornamental effect produced by the provision of the camera on the bag frame.

I claim:

The ornamental design for a combination handbag and camera or similar article substantially as shown and described.

THEODORE BALL.
